Attorney*

Patented Mar. 5, 1929.

UNITED STATES PATENT OFFICE.

JOHN L. NICHOLSON, OF CHICAGO, ILLINOIS, ASSIGNOR TO LOCOMOTIVE FIREBOX COMPANY, OF CHICAGO, ILLINOIS, A CORPORATION OF DELAWARE.

METHOD OF REPAIRING SIPHONS.

Application filed December 5, 1924. Serial No. 754,028.

This invention relates to improvements in methods of repairing siphons and consists of the matters hereinafter described and more particularly pointed out in the appended 5 claims.

The term "siphon" as herein used designates a flat hollow substantially triangular structure or element particularly adapted for use in locomotive boilers for increasing the 10 water circulation and steaming efficiency thereof. Such an element or thermic siphon is fully shown and described in my prior Patent No. 1,337,720 of April 20, 1920 and said element is located in the firebox of the boiler. 15 It generally includes a tubular bottom portion which terminates in a tubular extension or neck connected to the inner throat sheet and has a flat hollow body with an elongated discharge mouth, which opens through the 20 crown sheet of the firebox. Being arranged in the firebox as just mentioned, said tubular neck and adjacent body parts of the siphon which by reason of being located substantially close to the fire bed on the grate bars, are 25 subjected to the impingement or bombardment of the products of combustion as they pass from the fire bed to the boiler flues. This action of the products of combustion produces a real mechanical wear upon said parts which 30 being assisted by the continuous expansion and contraction under temperature changes, reduces the life of this portion of the siphon below that of the main body part thereof.

Because of their peculiar construction said 35 siphons are not only difficult to make, but due to the care with which they must be installed, they cost considerable. Heretofore such a worn siphon presented quite a problem. The major portion thereof is still serviceable 40 but the remaining portion is worn to that degree where safety demands its repair or the replacement of the entire siphon by a new siphon. The replacing of a siphon not only requires a great deal of time and labor to 45 remove the worn siphon, but also requires time and labor to reassemble and reweld the new one in place, thus causing a loss of service in said locomotive.

My present invention relates to a method 50 of repairing such worn siphons which method may be readily and economically carried out.

One of the objects of the present invention is to provide a simple and efficient method whereby the worn portion of the siphon may 55 be removed and a new portion substituted

therefor, thus restoring the siphon to its original efficiency at but a small expense of time and labor, at the same time reducing the service delay of the locomotive to a minimum.

Other objects of the invention as well as 60 the many advantages thereof will more fully appear as I proceed with my specification.

In the accompanying drawings:

Fig. 1 is a view in side elevation of a siphon element as it appears relative to the inner 65 throat sheet and crown sheet of a locomotive boiler firebox in which it is installed.

Fig. 2 is a view in side elevation on an enlarged scale of the siphon element after having been repaired by means of my improved 70 method.

Fig. 3 is a perspective view of my improved 75 half siphon or repair element as it appears ready for attachment to a siphon body, after the worn part has been removed.

Fig. 4 is a detail sectional view on an enlarged scale as taken on the line 4—4 of Fig. 2.

Fig. 5 is another detail sectional view as taken on the line 5—5 of Fig. 2.

Referring now in detail to that embodiment of the invention illustrated in the drawings:—1 indicates the crown sheet of a locomotive firebox, 2 the inner throat sheet thereof and 3 indicates as a whole a siphon or water steaming and circulating element, installed in the firebox and secured in said crown sheet and front throat sheet, as will soon appear. As described in my patent hereinbefore referred to, said siphon or element includes an upwardly and rearwardly 90 inclined tubular bottom or neck portion 4 and a progressively upwardly enlarging and generally triangular, flat hollow body portion 5. The lower part of the bottom portion is a closed tube and constitutes the neck 95 or intake portion 6 of the siphon or element which is in open communication with the front water leg by means of an annularly corrugated diaphragm plate 7 secured in a suitable opening provided thereof in said throat plate. The neck projects into the diaphragm plate and is preferably welded therein, said plate accommodating the expansion and contraction of said element under temperature changes. The hollow body portion 5 comprises parallel side walls 8—8 which are spaced apart a distance less than that approximating the diameter of the tubular or bulged portion 4 which gradually is reduced in width as it approaches the top end of the side

105
110

walls 8—8. Said walls terminate in an outwardly extending flange 9 which is welded into an opening in the crown sheet 1 provided therefor. The front end of the body 5 is defined by a transversely rounded wall 10 which is inclined forwardly and upwardly from the neck 6 as shown and to which it is connected by a curved elbow part 11. Such an element is formed by a single piece of heavy sheet metal folded upon itself with the median line of the tubular part 4 as the line of the fold, the two parts of the element meeting and being welded in a line defining the middle portion of the front wall 10 as shown at 12. The top end of the element, inside the flange 9, provides a discharge mouth which opens through the crown sheet to the discharge water and steam into the boiler space above the same. The side walls of the siphon 20 or element are suitably stay-bolted to withstand both internal and external pressure and the stay-bolts 13 are so disposed as to extend in rows parallel with lines defining the outlines of the element as a whole. The neck portion 6 is also stay-bolted as at 14.

In service the lower portion and bottom end of the body 5 together with the neck 6 is subjected to the greatest wear for the reasons before stated. Although the siphons are in active use for a long period of time before this wear is manifest, inspections from time to time will determine when said element should be repaired. When said repair is to be made, the worn part of the siphon or element is removed by cutting the same away as for instance with a torch along the dotted line 15, as shown in Fig. 1 so that both side walls are of an equal height. The middle or major portion of this line is arranged in a plane between the first two rows of stay-bolts 13 adjacent the tubular portion 4, said major portion being of an undulatory formation, the reverse curves thereof being arcs described about the stay-bolts of said first two rows as centers. In this manner sufficient metal is left about the holes of the second row of stay-bolts which are removed to be replaced by others, as will later appear, so that said side walls are not unduly weakened. The right hand end part 15^a of the line 15 passes through the end wall 10 in a plane between the second and third row of stay-bolts parallel with said portion 4 while the left hand end 15^b of said line passes through said portion 4 in a plane at a right angle thereto. In this instance, the line of cutting 15 is the same on both side walls.

To take the place of that worn portion of the siphon which has been removed as above described, I provide a renewal or repair boot or section which is substantially a duplicate of the removed part of the siphon except that its side walls are of a height greater than the side wall portions of the siphon which were cut away or removed and the neck thereof is

somewhat longer so that it may be trimmed to fit the old or new diaphragm plate 7 whichever the case may be. In Fig. 3 I have shown a perspective view of said repair boot or section before it has been installed in place. Said section comprises a tubular portion 4^a which terminates at one end in a tubular neck 6^a. Said tubular portion has parallel side walls 8^a—8^a of equal heights, which side walls have lower end extensions 8^b—8^b of greater height, which extensions are spaced apart until the tubular neck 6^a is approached. In the top right hand corner of said extensions are provided plug holes 16 and following the plane of said tubular portion 4^a two rows of stay-bolt openings 17 and 18 are provided. The neck 6^a of said repair element is stay-bolted as at 14^a.

When such a repair element is positioned in place with respect to the cut-away portion of the siphon 3, the top edges of its side walls 8^a, will overlap the bottom cutaway side walls of the siphon as shown in Fig. 2, the major portion of the top edge of said side walls 8^a being arranged in a plane between the second and third row of stay-bolts extending parallel with said tubular portions 4 and 4^a, respectively. The stay-bolt openings 18 of the repair element are brought into register with the line of stay-bolt openings adjacent the undulatory bottom edge of the side walls 8 of the siphon and a new row of stay-bolts 18^a are employed to secure the overlapping side wall parts together. A row of stay-bolts 17^a is then inserted in the openings 17 after which the bottom front ends of the side wall portions of the repair elements are worked over toward each other to embrace the bottom end of the end wall 10. Suitable holes are then drilled in said end wall in registry with the holes 16, after which screw plugs 20 are inserted in said holes and are riveted over; the meeting edges of the portions 8^b—8^b being welded together and to said end wall by a line of welding 21, as shown in Fig. 5. The edges of the side walls of the repair section are then welded to the adjacent face portion of the side walls of the siphon as indicated at 22, which welding also follows the end portions 15^a—15^b of the line of cutting on the siphon as indicated at 22^a—22^b in Fig. 2. As shown in Fig. 4, I prefer to offset the top portions of the side walls 8^a—8^a of the repair element outwardly with respect to the bottom portions so that said bottom portions are arranged in the plane of the side walls 8 of the siphon, thus eliminating the necessity of materially increasing the width of the repaired siphon at this point. The neck 6^a of the boot or repair element is then inserted in and fitted to the diaphragm plate 7 and welded thereto, whether said plate be the old or a new one.

In this manner a new bottom end is provided for the siphon which siphon will be just as efficient for its intended purpose as an

entirely new one. By overlapping the side walls of the repair element with respect to the body of the siphon and by the welding as before described, a strong and rigid, pressure tight connection is secured.

The improved method may be readily carried out at but a small expense when considered in the light of the expense of substituting an entirely new siphon for a worn one. The method may be also readily carried out with the tools and appliances found in any locomotive repair shop so that no new equipment need be purchased to practice the same.

While in describing my invention, I have referred to certain details of construction and steps in operation and the like, I do not wish to be limited thereto except as may be pointed out in the appended claims.

I claim as my invention:

1. The method of repairing a water steaming and circulating element of a boiler, which element has parallel side walls stay-bolted together, said method consisting in removing the worn portion of said element from the remainder thereof, in providing a new part to take the place of the removed portion which new part has side walls, in positioning said remainder and said new part together with the side walls thereof in overlapping relation, welding said overlapped parts of said side walls together along one edge of one of the overlapped side wall parts, and in then stay-bolting the overlapped walls on one side of the element to the overlapped side wall parts on the other side of the element.

2. The method of repairing a water steaming and circulating element in a locomotive firebox which element comprises spaced parallel stay-bolted side walls connected to the crown sheet of the firebox and a tubular neck

connected to the inner throat sheet of the firebox, which method consists in removing the worn part of said element along parallel undulatory lines, the curves of which are formed about predetermined stay-bolts as centers, in removing said stay-bolts, in providing a new part to take the place of the worn portion which new part has side walls with stay-bolt openings therein, in positioning said new part with respect to the remainder so that the side walls of said new part will overlap the side walls of the remainder with the stay-bolt openings in registration, in arranging stay-bolts in said openings and then welding said overlapped side wall parts together along a line defined by the edges of one of said side wall parts.

3. The method of repairing a water steaming and circulating element of a boiler which element has parallel side walls stay-bolted together, said method consisting in removing the worn part of said element from the remainder thereof along undulatory lines, the curves of which are formed concentric to predetermined stay-bolts, in removing stay bolts, in providing a new part to take the place of the worn portion which new part has side walls spaced apart greater than the distance of the part removed and provided with stay-bolt openings therein, in positioning said new part with respect to the remainder so that the side walls of said new part will embrace and overlap the side walls of the remainder with the stay-bolt openings in registration, in arranging stay-bolts in said openings and then welding said overlapped side wall parts together along a line defined by the edges of one of said side wall parts.

In testimony whereof, I have hereunto set my hand, this 1st day of December, 1924.

JOHN L. NICHOLSON.
